COUPON BOOK

Billups Harris, Columbus, Miss.

Application October 31, 1936, Serial No. 108,669

5 Claims. (Cl. 283—6)

This invention relates to sales or coupon books in which a number of individually detachable coupons or tickets are bound into book form, each coupon representing a certain purchasing value in exchange for merchandise, and the book being purchased by customers for a fixed sum, usually less than the aggregate value represented by the coupons, as an inducement to the purchase of the book.

10 The primary object of the present invention is to provide a further inducement to the purchase of the books, and with this end in view, the invention consists of a novel construction and arrangement of the parts, wherein the element of chance is introduced by the incorporation in certain of the books (the particular ones being unknown both to the seller of the book and to the purchaser) of a concealed symbol entitling the purchaser of a book bearing this symbol to a refund of the purchase money.

20 Further objects will appear as the description proceeds in connection with the appended claims and attached drawing wherein:

Figure 1 is a plan view of the improved coupon book in open condition, to show the construction and relation of the parts of the same;

25 Figure 2 is a perspective view of the same in closed or sealed condition, in the form in which the book will be furnished by the manufacturer to the salesman or dealer, and sold by him to the customer;

30 Figure 3 is a similar view, showing the book partially opened by rupture of the first seal; and

Figure 4 is a fragmental view similar to Figure 3, showing the second seal ruptured to expose the part which may bear the symbol indicating that the book with such symbol will entitle the purchaser to a refund of the purchase price; and

35 Figure 5 is a plan view illustrating a modified seal for use in the present invention.

40 Referring to the drawing:

As best shown in Figure 1, the coupon book consists of a block of coupons 1 bound between front and back covers 2 and 3, the said block comprising leaves of coupons, each leaf in the present instance bearing three coupons 4 separable from each other by horizontal weakened lines 5, and separable from the stub or bound-in portions of the leaves by vertical weakened lines 6, these coupons representing a certain predetermined purchasing value, which is printed thereon as shown.

Attached to the outer edge of the front cover 2 is a folding flap 7, designed to carry on its inner face a symbol 8, which in the present in-

stance is the representation of a four leaf clover, although it will be understood that any other symbol, sign, figure or mark may be employed. Certain of the books of a given number thereof will bear such symbol, which will entitle the purchaser of the book bearing this symbol to a refund of the purchase price thereof.

At the junction of the flap 7 with the cover 2, there is provided a weakened line 7a, the purpose of which will presently appear; and the flap is adapted to be sealed down against the inner face of the cover in such manner that the seal may be readily broken to release the flap, in order that the purchaser of the book may determine whether or not the flap bears the lucky symbol. In the present instance this is effected by applying to the inner face of the flap at opposite ends thereof, adhesive coatings 8a, and forming parallel weakened lines 9 in the flap at the inner edges of the coatings, whereby the flap can be pasted down against the face of the cover 2, as shown in Figs. 2 and 3, and can be released or removed therefrom by tearing along the weakened lines 9 to enable the flap to be turned outwardly, or torn off along the line 7a, and thereby expose its inner face, as shown in Figure 4.

Attached to the outer edge of the back cover 3 is an extension flap 10 having its inner face covered with adhesive 11, and adapted when the back cover is closed and the flap 7 is sealed against the inner face of the front cover, and the latter is closed, to extend around the outer edges of the coupons and the front cover and lie flatly against the outer face of the latter where the extension flap is pasted down by the adhesive coating, as shown in Figure 2.

Where the extension flap 10 joins the back cover, a weakened line 12 is formed to enable the back to be opened by the customer to permit access to the sealed flap 7.

Figure 2 shows the book in closed sealed condition, as effected by the first seal, which book may be opened by tearing along the weakened line 12; and sealed also by the second seal which may be ruptured by tearing along the weakened lines 9 to release the symbol-bearing flap, it being understood that the book is delivered by the manufacturer to the dealer (who will sell them to his customers) in the completely sealed condition as shown in Fig. 2.

The customer when he purchases a book, will break the first seal by tearing along the weakened line 12 of the outside cover, which will permit the book to be opened to the position shown in Figure 3, where it will be seen that, while the

coupons are exposed, the symbol bearing the flap 7 is still sealed down. The purchaser then tears the flap 7 along the weakened lines 9, and also along the weakened line 7^a, so as to detach the 5 flap from its sealed condition and enable it to be determined whether or not it bears the lucky symbol. If the detached flap bears the prearranged symbol, the flap will be delivered to the seller of the book, and he will return the purchase 10 money to the purchaser.

In this way, a very attractive inducement is offered to the purchaser of the book on the chance that, due to the fact that a certain number of the books offered for sale will bear the lucky symbol, the purchaser will secure a book with such 15 symbol.

The fastening of the symbol-bearing flap 7 down by adhesive at its opposite ends as described, precludes the possibility of anyone, before the seals are broken by the legitimate purchaser, from ascertaining, by peering into the 20 ends of the book, if it bears a symbol, which, in the absence of the sealing of the flap at its ends, might be accomplished by bowing or bending the 25 covers of the book outwardly.

It will be noted that, due to the fact that the extension flap 10 is pasted down against the outer face of the front cover 2, and due to the fact that the symbol-bearing flap 7 may be detached from the cover 2, the coupon book will, 30 after the same has been thus opened by the customer, retain its true book form, with no extensions on either the front or rear covers, such as these covers had before the book was opened.

The construction of the book as a whole is very simple and compact, and convenient to handle, both in its sealed condition as shown in Fig. 2, and in its unsealed or opened condition as shown in Figures 3 and 4; and due to the method of concealing the lucky symbol from all except the 40 authorized purchaser, and the method by which access is gained to the same by the authorized purchaser, the element of chance thus introduced, offers to the purchaser a very attractive and inviting inducement, aside from any inducement offered by the reduction in the price of the book 45 from the face value of the coupons.

In Figure 5 a modified form of sealing means is illustrated, the same reference numerals being 50 used to indicate the same parts in this form of the invention. As seen in Figure 5, flap 10 is provided with end tabs 16 having securing tabs 17 formed thereon. Tabs 16 are designed to be bent over the ends of the book and tabs 17 are inserted through slots 18 provided in back cover 3 as shown in dotted lines at the lowermost end of the book. The overhanging portions 19 of tab 17 are interlocked with the cover member 3 so that the tabs 17 cannot be withdrawn. When 60 the purchaser receives the book he tears tabs 16 along weakened lines 21 between the tabs and flap 10 thereby freeing the flap 7 and coupons 10. Flap 7 may then be torn off along line 7^a and the tabs 17 removed to leave the book in 65 convenient form for use by the purchasers.

The invention may be embodied in other specific forms without departing from the spirit or

essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein. 5

What is claimed and desired to be secured by 10 United States Letters Patent is:

1. In a coupon sales book including a series of coupons and a cover therefor, a flap, having a symbol on its inner face, formed on an outer edge of said cover; means for fastening said flap 15 throughout its upper and lower margins to a face of said cover with the symbol concealed; and means inwardly of said fastened margins of said flap weakening said flap along lines parallel to said margins whereby said flap may be severed 20 along said weakened lines to expose the concealed symbol.

2. The structure set forth in claim 1, characterized by the fact that the flap therein mentioned is fastened down on the cover by adhesive applied to the margins only of the flap, and that weakened lines are provided in the flap at the 25 inner edges of the adhesive to release said flap.

3. A coupon sales book including front and rear covers and coupons bound between the same; comprising a symbol-bearing flap on the front cover sealed down releasably on the inner face of the cover to conceal the symbol, an extension flap on the rear cover extending around the outer edges of the coupons and the front cover, and a 30 fastened down on the outer face of the front cover, and a weakened line at the junction of the extension flap with the back cover for separation of said extension flap and back cover in opening the book to gain access to the symbol-bearing flap. 35

4. A coupon sales book, including front and rear covers and coupons bound therebetween, a flap having a symbol on its inner face formed on an outer edge of the front cover, means for releasably fastening the flap face down against the inner face of the front cover with the symbol concealed, an extension flap on the rear cover extending around the outer edges of the coupons and front cover, means for fastening the extension flap down on the outer face of the front cover, and a weakened line at the point of connection of the extension flap with the back cover adapted to be ruptured to open the book. 45

5. Indicia concealing means for use in a coupon sales book including a series of coupons and a cover having one or more indicia thereon comprising a flap formed on an edge of the cover, means for releasably fastening the flap face down against an inner face of the cover to conceal the indicia, a second flap on another edge of said cover extending around the first mentioned edge of the cover, means for fastening said second flap down on the outer face of said cover and a weakened line at the point of connection of said second flap and the cover adapted to be ruptured to open the book. 55
